TOILET PAPER HOLDER

Joseph Garson, New Haven, Conn.

Application December 8, 1941, Serial No. 422,074

4 Claims. (Cl. 91—46)

This invention relates to a new and improved toilet paper holder and moistener, having as a principal object thereof to provide a device of this character wherein the paper will be automatically moistened and impregnated with a disinfectant and of such simple construction that it may be economically produced and readily secured in a fixed position.

To these and other ends, apparent from the following description and the accompanying drawing, the invention consists in the toilet paper holder and moistener, having certain details of construction and combinations of parts as will be hereinafter described and more particularly pointed out in the claims.

Referring to the drawing, wherein like numerals of reference indicate like parts in the several figures;

Figure 1 is a perspective view of the improved toilet paper holder and moistener secured to a fixed object, such as a wall; and

Figure 2 is a side elevation thereof.

The holder comprises in part a substantially U-shape frame, having two side arms 11 and 12, which terminate at their free ends in a coil portion, through which project fastening screws 14 to secure the holder to a wall or structure 13.

Extending across the open space between the arms 11 and 12 is a roll bar 10, hinged at 15 on the arm 12 between ears 16 at one end, and the opposite free end 17 of which is held in a closed position by a clip 18 of any convenient construction. Upon the bar 10 is a roll R of toilet paper, the assembly of which is accomplished by slipping the roll over the bar after releasing it from the clip 18 and moving it into a convenient position at an angle to its position as shown in the drawing, after which the roll bar 10 is restored to its former horizontal position and locked by the clip 18.

On that arm of the frame between the side arms 11 and 12 a reservoir is hinged at its upper end, at 19. This reservoir, which contains a liquid, which may be a disinfectant, is held against relative movement by the lock bars 28, that are mounted to move freely on the arms 11 and 12, and having a hooked engagement at their opposite ends with sockets 29, in a well known manner. The contents of the reservoir 20 may be emptied therefrom by swinging the same upon its hinged mounting to substantially the position shown by broken lines in Figure 2, after releasing the lock bars 28 from the sockets 29.

Upon each of the opposite ends of the reservoir 20 is a guide plate 21, through which project the

arms of the roll carrier 22. These arms are joined outside of and under the reservoir 20 by the intermediate portion 26, which in its up position is held by a clip 27 or the like of substantially the same construction as the clip 18. The arms of the roll carrier 22, above the reservoir 20, are turned downwardly at 23 and inwardly at 24, upon which is rotatably mounted the transfer roll 25. The paper from the roll R, in substantially the position shown in the drawing, is passed under the roll 25 and torn off in lengths as desired.

If it is desired that the paper be moistened or impregnated, the roll 25 is released from its clip holder 26 and then falls by its weight onto the paper, which lowers the same into the liquid in the reservoir, the roll then being on the dotted line position substantially as shown in Figure 2 and the paper passed thereunder. The contact of the paper with this wet roll moistens the same before it is torn off.

A moistened or impregnated pad of paper may be obtained by first drawing off a sufficient length of moistened paper and then folding the same back onto itself as many times as desired. If it is preferred that the exterior of the pad be dry and the interior portion moistened or impregnated, then after the moistened paper has been folded into a pad, dry paper is taken from the roll and placed on the outside of the moistened portion in as many layers as may seem expedient.

Within the scope of the appended claims, minor changes and alterations may be made in the preferred embodiment of the invention disclosed herein.

35. What is claimed is:

1. In a toilet paper holder and moistener; a frame; means for securing the same in a fixed position; a roll bar hinged thereon; a reservoir hinged thereon; a transfer roll movably connected with the reservoir; and means for holding the transfer roll in a position above the liquid in the reservoir.

2. In a toilet paper holder and moistener; a frame; means for securing the same in a fixed position; a roll bar hinged thereon; a reservoir hinged thereon; a roll carrier movably mounted on the reservoir; and a transfer roll rotatably mounted on the roll carrier.

3. In a toilet paper holder and moistener; a frame; means for securing the same in a fixed position; a roll bar hinged thereon; a reservoir hinged thereon; a guide plate at opposite ends of the reservoir; a roll carrier movably mounted in the guide plates; and a transfer roll rotatably mounted on the roll carrier and by manipulation

thereof moved into and out of the liquid in the reservoir.

4. In a toilet paper holder and moistener; a frame; means for securing the same in a fixed position; a roll bar hinged thereon; a reservoir hinged thereon; a guide plate at opposite ends of the reservoir; a roll carrier formed with arms that

project upwardly from a bottom portion upon each side of the reservoir and through the guide plates upon the sides thereof; and a transfer roll supported by the said arms across the open end of the reservoir.

JOSEPH GARSON.
